POT TYPE OIL BURNING SPACE HEATER

Charles T. Piehl, Batavia, N. Y.

Application May 4, 1938, Serial No. 205,956

4 Claims. (Cl. 158—91)

The invention relates to improvements in a liquid fuel oil burner with adjustable baffle plates inside the pot or burner by which the flame may be controlled by raising or lowering the baffles 5 and the sleeve arranged outside of the burner which sleeve regulates the air supply to the burner and gives a perfect combustion on a low, medium or high flame without carbon or smoke.

In order that the invention may be clearly understood, reference is to be had to the accompanying drawing in which Figure 1 illustrates an elevational view of the heater with combustion chamber and burner. Figure 2 shows the front of the heater cut away, showing baffles 15 and flame spreader with controls connected to the outer sleeve to which the adjustable baffles are bolted. Figure 3 is a plan view of the baffles with opening in center. Figure 4 shows another view of the baffles with flame spreader and studs 20 to space the baffles and to which the baffles are fastened. Figure 5 shows control by means of which the baffles are raised and lowered and locked to hold the baffles in any position. Figure 6 is a plan view of the damper which prevents the heat from rushing up the chimney.

Figure 7 shows plates which fasten to the outside of burner where brackets pass through to connect baffles to the sleeve on the outside of burner.

Figure 8 shows the burner with perforations through which the air passes from the outside to inside of the burner.

In Figure 1 No. 1 is the outside sleeve to which baffles 14 are fastened. No. 2 is the rod that connects sleeve 1, to control in Figure 5 by which baffles 14 and sleeve 1 are raised and lowered. 12 is the combustion chamber. 17 is the burner. 4 shows gear teeth in connecting rod. 18 shows opening for oil pipe connections. 19 shows plate riveted to burner. 5 is control wheel for raising or lowering baffles 14 and sleeve 1. 10 is a tube that passes through combustion chamber 12 and fastens in place with lock nuts on the inside and outside combustion walls 12. The numeral 11 indicates the rod that passes through tube 10 to which gears 3 are fastened, which gears engage teeth 4 of connecting rods 2. Gear 6 is stationary and is fastened to frame 8. Rod 11 which passes through tube 10 has square ends on which gears 5 are fastened so that they will rotate with rod 11. Gears 6 and 7 form a ratchet and are locked in place with spring 9. When control wheel 5 is pulled outward from chamber 12 it releases gear 7 from gear 6, then the control wheel 5 is turned, 55 this will raise or lower baffles 14 and flame

spreader 15 and sleeve 1. 13 is the waste damper to keep the heat from rushing up the chimney and it is mounted in the combustion chamber 12 just below the smoke outlet pipe 24. Baffles 14 are fastened to sleeve 1 on four sides with arms 21. Arms 21 pass through slit 20 in plate 19 on burner 17 and connect to sleeve 1 to which they are bolted. Plates 19 have their edges bent outwardly so as to form a guide in which cover 22 slides vertically. As baffles 14 and sleeve 1 are raised or lowered cover 22 covers up slit in plate 19 so that the burner 17 can not take in air at this point. 23 shows a small opening in cover 22 large enough to admit arms 21.

Sleeve 1 controls the air inlet in burner 17 in connection with baffles 14 by being able to control the air inlet in burner 17 and being able to raise the baffles increasing the combustion space in the bottom of burner, it can be operated on much less fuel consumption and still have a clean fire with perfect combustion. This burner can be operated at any stage, low, medium or high flame, raising sleeve 1 and baffles 14 according to how much fuel is turned into the burner 17 which gives it the proper amount of air through the small holes in burner 17. This will always burn without forming carbon in burner 17 and combustion chamber 12. The height of flame can be increased and decreased without increasing or decreasing fuel consumption by raising or lowering sleeve 1 and baffles 14.

I am aware that prior to my invention, pot type oil burning space heaters have been made with stationary baffles without adjustments while the burner is in operation except for turning the fuel on and off.

I claim:

1. In an oil burner, a cylindrical body portion comprising a lower burner chamber and a combustion chamber above the burner chamber, said burner chamber having a plurality of openings formed in the wall thereof, movable deflector plates mounted within the burner chamber, means for securing the deflector plates in spaced relation with each other, a sleeve movable over the body portion and openings, regulating the passage of air into the burner chamber, and means for adjusting the deflector plates and sleeve simultaneously.

2. In an oil burner, a cylindrical body portion comprising a lower burner chamber and a combustion chamber above the burner chamber, said burner chamber having a plurality of openings formed in the wall thereof, superposed deflector plates spaced apart and having central aligning

openings, mounted within the burner chamber, means for connecting the deflector plates, a vertically movable sleeve mounted for sliding movement on the body portion and adapted to control the passage of air to the burner chamber through said openings, and means for operating the deflector plates and sleeve simultaneously.

3. In an oil burner, a cylindrical body portion comprising a lower burner chamber and a combustion chamber above the burner chamber, said burner chamber having a plurality of openings formed in the wall thereof, superimposed deflector plates arranged in spaced relation with each other and having aligning central openings through which products of combustion pass upwardly to the combustion chamber, a spreader plate spaced from the uppermost deflector plate and overlying the opening thereof, a sleeve mov-

able over the body portion and adapted to regulate the quantity of air passing into the burner chamber regulating combustion within the burner chamber, and means for moving the deflector plate and sleeve simultaneously.

4. In an oil burner, a cylindrical body portion comprising a lower burner chamber and a combustion chamber above the burner chamber, said burner chamber having a plurality of openings formed in the wall thereof, deflecting members within the burner chamber and adapted to control the passage of products of combustion to the combustion chamber, a sleeve operating over the burner chamber and adapted to regulate the quantity of air passing into the burner chamber, and means for moving the sleeve and deflector means simultaneously.

CHAS. T. PIEHL.
